UNITED STATES PATENT OFFICE.

ALBERT A. KELLOGG, OF KANSAS CITY, MISSOURI.

AEROPLANE.

1,377,490.

Specification of Letters Patent. Patented May 10, 1921.

Application filed July 27, 1920. Serial No. 399,300.

To all whom it may concern:

Be it known that I, ALBERT A. KELLOGG, a citizen of the United States, residing at Kansas City, in the county of Jackson and State of Missouri, have invented certain new and useful Improvements in Aeroplanes, of which the following is a specification.

This invention relates to aeroplanes, and particularly to a structure of this character adapted for safe landing of the plane.

The primary object is to construct a craft of this character which can be instantly converted into a parachute to thus insure safe landing of the plane when this may be necessitated through accident, or to suit the desire of the operator.

A further object is to so construct the machine, that the parachute structure is included and embodied in a manner to vary the machine but little from standard machines as now in use, and with which the same ease in flying and facility of control as with standard machines is possible.

25 A further object resides in constructing the plane with a detachable fuselage or body, which can be dropped in case of accident, to thus lighten the parachute structure and give same greater sustaining power.

30 A still further object lies in providing controls by which the greatest parts of the machine included within the scope of my invention can be readily set, shifted, and manipulated from the operator's seat, and including means with the parachute structure whereby the travel of the same in its descent can be controlled.

Still another object is to provide for swinging the propeller to operate in a horizontal plane, upon the helicopter principle, to aid in sustaining the weight of the machine, when a landing is being made with the engine still running; and, in arranging the aft portion of the fuselage to be opened 45 or spread to increase the sustaining surfaces to balance the lifting force exerted by the propeller when so shifted.

Yet another object is to so construct and arrange the parts that they may be included without the necessity of re-designing the standard aeroplane, and that the embodiment may be accomplished at a minimum expense.

With these objects in view, the aeroplane, constructed in accordance with my invention, includes within the lower sustaining

plane a plurality of flaps which are raised upwardly to open out against the struts and which leave the middle of the lower plane open and present a pocket or parachute structure in which the upper plane is the top, control means being provided within reach of the operator for holding and releasing the flaps and for manipulating the same; and, in associating with this plane structure a body or fuselage adapted to be disconnected from the plane structure and dropped from the machine to increase the sustaining power of the parachute.

This invention includes certain novel features of construction and combinations of parts which will be set forth in connection with the drawings, in which:

Figure 1 is a perspective view of an aeroplane constructed in accordance with my invention.

Fig. 2 is a view similar to Fig. 1, showing the aeroplane converted into its parachute form and illustrating the manner in which the detachable portions of the fuselage are dropped.

Fig. 3 is a fragmentary plan view showing one end of the lower plane.

Fig. 4 is a sectional view on the line 4-4 of Fig. 3.

Fig. 5 is a sectional view through the upper and lower planes at one end of the machine, showing the flaps raised.

Fig. 6 is a sectional view through the upper and lower planes adjacent the fuselage, to show the means for securing the same to the plane structure.

Fig. 7 is a longitudinal sectional view through the middle portion of the body, to better show the controls.

Fig. 8 is a sectional view on line 8-8 of Fig. 7, taken transversely through the fuselage.

Fig. 9 is a fragmentary perspective view of the flap holding and releasing means.

Fig. 10 is a detail sectional view showing the fuselage locking means.

Fig. 11 is a detail view of the locking disk embodied in the locking means.

Fig. 12 is a view in end elevation of the machine, showing the propeller shifted to rotate in a horizontal plane.

Fig. 13 is a sectional view transversely through the aft part of the fuselage; illustrating an arrangement for increasing the parachute and plane surface.

In its main frame, the aeroplane struc-

ture is of substantially the same form and design as standard machines now in use, this structure including the upper and lower planes 1 and 2, and the body 3. The body 5 is made up of a middle portion 4, which is built on and is affixed as a part of the plane structure, and the forward and rear portions 5 and 6, carried by side stringers 7. The forward portion carries the engine, by 10 which the propeller 8 is driven, and the rear portion has the usual tail structure, generally indicated at 9, and including the rudder, elevator, and stabilizer mounted thereon. A landing gear is mounted at 10, in 15 conjunction with the detachable portion of the body, a tail skid is provided on the rear portion of the fuselage, landing skids 12 are positioned at the ends of the lower plane 2, and in other features and respects the 20 aeroplane structure is designed and constructed for efficient operation.

The upper and lower planes 1 and 2 are spaced by struts 13, and have the usual brace wires 14 connected therebetween, these 25 struts and brace wires being disposed to substantially inclose the space within the struts on each side of the fixed body portion 4. The struts 13 are connected with the front spar 15 at the leading edge of the 30 lower plane, and with the rear spar 16 at the trailing edge, and in this way the middle portion of the lower plane is left free. Between the front and rear spars the middle of the 35 lower plane is left free. Between the front and rear spars the middle of the lower plane is left open substantially as shown in Fig. 5, and flaps 17 and 18 are hinged at the forward and rear sides of the opening, flaps 19 and 20 being hinged on the plane structure 40 at those edges of the openings opposite the fixed body portion 4.

The arrangement of these flaps is such that when released from the positions shown in Figs. 1, 3 and 4, and swung up to the 45 positions illustrated in Figs. 2 and 5, they will substantially fill the space between the lower and upper planes, and will shut in that area defined by the spars 13 and brace wires 14, these spars and brace wires offering 50 support to the flaps.

At the hinge joints of each of the wing flaps 17 and 18 hand levers 20 and 21 are secured, and by manipulation of these hand levers, the flaps can be inclined slightly forwardly, as shown by the dotted lines in 55 Fig. 5.

The flaps 17 and 18, together with the end flaps 19 and 20, are closed down within the openings at the ends of the plane 2, 60 and to properly stretch the end flap 17 a batten 22 is provided at its loose edge to be engaged by a strap 23 on the upper flap. By this arrangement the lower flap is stretched and drawn taut across the opening to form 65 substantially a continuation of the lower

plane surface. The end flaps 19 and 20 may be closed down between the flaps 17 and 18, or may be laid over on top of these flaps, and to retain the several flaps in their closed position, I provide retaining bars 24, 70 which are held by links 25 pivoted on the structure of the lower plane 2. These retaining bars are connected at their inner ends to an operating lever 26, after the manner shown in Fig. 9, and as the lever is 75 shifted in one direction, the retaining bars 24 will be swung out around the pivotal mounting of links 25 to rest over the flaps 18 at their forward edges and hold the same against opening, the movement of the 80 lever 26 in the opposite direction swinging the retaining bars 24 from the position over the flaps 18. This operating lever 26 is located within the fixed body portion 4 and, with levers 20 and 21, is placed to be readily 85 accessible to the operator.

The plane structure as hereinabove described includes posts 27 which are mounted between the planes 1 and 2, on opposite sides at the front and rear of the fixed 90 body portion, and the construction of the fuselage and body portion is such that the line of separation is defined by these posts. Cross stringers 28, which are provided as part of the detachable fuselage 95 structure, have short posts 29 and 30 hinged thereon on opposite sides of the detachable fuselage at the front and rear, these hinged posts being adapted to be closed against the posts 27, as illustrated in Fig. 6, and to 100 swing therefrom as shown by the dotted lines. The posts 27 have socket openings 31 therein and studs 32 are provided on the short posts 29 and 30, and fit within these sockets when the fuselage is adjusted 105 to the proper position with respect to the plane structure.

To retain the posts 29 and 30 in position against post 27, the structure shown in Figs. 10 and 11 is employed. This locking means 110 includes the locking disks 33, which are rotatably mounted on the posts 29 and 30, and which have arms 34 extending therefrom through which rotative movement is accomplished. These locking disks have 115 cam slots 35 and 36 in the face thereof, and the cam slots are adapted to receive hook arms 37 and 38, which are carried pivotally on the yokes 39 mounted on the inner sides of posts 27 and held in place by connecting 120 rods 40. When the short posts 29 and 30 are swung up to engage the studs 32 thereof in sockets 31 of the posts 27, the hook arms are caught around these short posts and are fitted within the cam slots 35 and 36, after 125 which locking disks 33 are rotated to force the hook arms inwardly and to retain the hook portions over the short posts, and when the short posts are to be released, reverse rotation of the locking disks will force the 130

hook arms from this engaged position and will throw the same from the short position to thus leave these posts free to fall back upon their hinged connections, and thus 5 withdraw the studs from the sockets.

To accomplish simultaneous shifting of the several locking disks 33, the means shown in Figs. 7 and 8 may be employed. This includes a shaft 41, which is mounted in suitable bearings on the detachable fuselage structure, and which has arms 42 and 43 extending laterally therefrom, an operating lever being provided in the forward part 5 of the detachable fuselage, to rotate 10 this shaft and to consequently swing the arms. Links or rods 45 are extended from the arms 42 and 43 and are connected with the operating arms 34 of the locking disks 33, and thus as operating lever 44 is swung 15 to one side or the other, the several locking disks 33 will be revolved to engage and hold the hook arms within the cam slots thereof or to force the hook arms from the retaining engagement around the short posts.

25 In the use of an aeroplane constructed in accordance with my invention, the several flaps in the lower wing or plane 2 will be closed and will be maintained in this closed position during the flight of the machine.

30 The machine may rise and land without these flaps being disturbed or opened, and in fact the plane may be flown and operated entirely as with standard aeroplanes now in use. However, if the engine stops or any 35 accident occurs, or circumstance arises, which necessitates a landing where the momentum of the machine is not sufficient for the usual planing descent, or where the landing space is limited, the operating lever 26 40 is shifted to withdraw the retaining bars 24. As the plane falls, the force of the air against these flaps will cause the same to open to the position shown in Fig. 2. The operating lever 44 is then shifted to release

45 the fuselage locking means and posts 29 and 30 fall back from the posts 31 on the plane structure. As the released portion of the fuselage contains the heavy weight of the machine and the plane structure is in 50 the form of a parachute, the fuselage will drop as shown in Fig. 2. The operator is then sustained and is gradually lowered by the parachute portions embodied in the plane structure and a gentle landing is accomplished.

55 During the descent of this parachute plane structure, the course can be guided, shifting the flaps 17 and 18 through the use of operating handles 20 and 21, substantially as shown by the dotted lines in Fig. 5, and in this way the direction of travel may be varied and the place of landing governed.

60 While it is desirable that the weight of the aeroplane structure be reduced by drop-

ping the fuselage, this means a loss of this portion of the machine, and furthermore occasion may arise when it is desirable to land the machine with the engine running. To this end, the machine may be constructed in 70 the manner shown in Fig. 12, where the engine structure at 46 is mounted by trunnions on bearing posts 47, to be swung to a position in which the propeller shaft is vertically disposed and the propeller 48 is rotated in a horizontal plane. With this shifting of the propeller, a helicopter action is accomplished and the weight of the engine is sustained. To add still further to the sustaining surfaces of the machine, it may be 75 found desirable to construct the rear portion 49 of the fuselage substantially as shown in Fig. 13, where the sides 50 and 51 are hinged to swing outwardly at their lower edges, arcuated rods 52 being provided to 80 limit the opening movement of these sides. A cable 53, or other suitable means, may be employed to draw in the sides 50 and 51 to close the fuselage, and the opening and closing of these sides may be controlled by any 85 suitable means within the reach of the operator.

90 It will be understood that the several operating levers, and, in fact, all controls and parts as set forth are herein shown in 95 dependently of the usual control for the aeroplane; but, in practice, these controls might be embodied in or connected with the control levers and control mechanism by which the machine is operated. Further, 100 while I have described specific embodiments and have mentioned only certain possible modifications, it is to be understood that in practice I do not wish to limit myself entirely to the details as herein set forth, but 105 may resort to any practical modifications falling within the scope of the invention as defined in the appended claims.

I claim:

1. An aeroplane including with spaced 110 upper and lower planes, the lower plane having an opening in its center, flaps hinged at edges of the opening to be swung down to close the same and to swing up to provide a parachute structure of which the upper 115 plane forms the top.

2. An aeroplane including with spaced 120 upper and lower planes, the lower plane having an opening in its center, flaps hinged at edges of the opening to be swung down to close the same and to swing up to provide a parachute structure of which the upper plane forms the top, and releasable means to hold the flaps in the closed position.

125 3. An aeroplane including with upper and lower planes spaced one above the other, the lower plane having openings in its center at each end, flaps hinged at the forward and rear sides of the openings, and other flaps 130

hinged at the ends of said openings, the arrangement of the various flaps being such that when swung down they close the openings of the lower plane and when swung up 5 these flaps provide a parachute structure in which the upper plane forms the top.

4. An aeroplane including with upper and lower planes spaced one above the other, the lower plane having openings in its center at 10 each end, flaps hinged at the forward and rear sides of the openings, other flaps hinged at the ends of said openings, the arrangement of the various flaps being such that when swung down they close the openings of 15 the lower plane and when swung up these flaps provide a parachute structure in which the upper plane forms the top, and operating levers associated with the flaps hinged at the forward and rear edges of the openings 20 by which said flaps can be selectively moved and adjusted to direct the drifting course of the machine.

5. An aeroplane including with upper and lower planes spaced one above the other, 25 struts and brace wires by which said planes are connected, the lower plane having openings at each end within the space defined by the struts and brace wires, flaps hinged at the forward and rear sides of the openings, and 30 other flaps hinged at the ends of said openings, the arrangement of the various flaps being such that when swung down they close the opening of the lower plane and when 35 swung up these flaps stand substantially vertically against the struts and brace wires to provide a parachute structure in which the upper plane forms the top.

6. An aeroplane including with upper and lower planes spaced one above the other, 40 struts and brace wires by which said planes are connected, the lower plane having openings at each end within the space defined by the struts and brace wires, flaps hinged at the forward and rear sides of the openings, 45 other flaps hinged at the outer ends of said openings, the arrangement of the various flaps being such that when swung up they close the opening of the lower plane and when 50 swung up these flaps stand substantially vertically against the struts and brace wires to provide a parachute structure in which the upper plane forms the top, releasable means to hold the flaps in the closed 55 position, and operating lever by which the releasable means is actuated, and operating levers associated with the flaps at the forward and rear edges of the openings by which 60 said flaps can be selectively moved and adjusted to direct the drifting course of the machine.

7. An aeroplane including with spaced upper and lower planes, the lower plane having an opening in its center, flaps hinged at edges of the opening to be swung down 65 to close the same and to swing up to provide

a parachute structure of which the upper plane forms the top, a detachable fuselage structure for the aeroplane, and means by which the fuselage is connected with the plane structure to be released and dropped 70 to lighten the parachute structure.

8. An aeroplane including with upper and lower planes spaced one above the other and having a body portion associated therewith substantially at their longitudinal center, the lower plane having openings in its middle portion on each side of the body, flaps hinged at the forward and rear sides and the outer ends of said openings, the arrangement of the various flaps being such 80 that when swung down they close the openings of the lower plane and when swung up these flaps provide a parachute structure in which the upper plane forms the top, a detachable fuselage structure including forward and rear body portions, and releasable means by which the detachable fuselage structure is secured in conjunction with the plane structure in line with the body portion thereof. 90

9. An aeroplane including with spaced upper and lower planes, the lower plane having an opening in its center, flaps hinged at edges of the opening to be swung down to close the same and to swing up to provide a parachute structure of which the upper plane forms the top, a fuselage associated with the plane structure having its forward end extending in advance of the planes, a propeller and operating engine 100 furnishing driving power for the machine mounted in this forward extension, and a mounting for the propeller and engine by which the propeller is shiftable to revolve in a horizontal plane to accomplish a helicopter 105 sustaining lift against the weight of the engine.

10. An aeroplane including with spaced upper and lower planes, the lower plane having an opening in its center, flaps hinged at edges of the opening to be swung down to close the same and to swing up to provide a parachute structure of which the upper plane forms the top, a fuselage associated with the plane structure having its forward 110 end extending in advance of the planes, a propeller and operating engine furnishing driving power for the machine mounted in this forward extension, a mounting for the propeller and engine by which the propeller 115 is shiftable to revolve in a horizontal plane to accomplish a helicopter sustaining lift against the weight of the engine, and movable sides on the after part of the fuselage to 120 be opened to extend at an angle downwardly 125 and to increase the parachute sustaining surfaces of the aeroplane.

In testimony whereof I affix my signature.

ALBERT A. KELLOGG,
